US00D640708S

(12) **United States Design Patent**
Lee

(10) **Patent No.:** US D640,708 S
(45) **Date of Patent:** ** Jun. 28, 2011

(54) **SUPPORTER FOR PORTABLE COMPUTING DEVICE**

(76) Inventor: **Wen-Sung Lee**, Taichung (TW)

(**) Term: **14 Years**

(21) Appl. No.: **29/381,892**

(22) Filed: **Dec. 24, 2010**

(51) LOC (9) Cl. **08-07**

(52) U.S. Cl. **D14/447**

(58) **Field of Classification Search** D14/447, D14/451, 452, 448, 457, 432, 434, 440, 217, D14/250, 251, 253, 239, 373; D3/218; D6/406.3, D6/406.4, 406.5, 406.6; D8/363, 373, 380; 248/917-924, 139, 149, 150, 155.2, 371, 248/415, 176.3, 324, 687, 688, 441.1, 447, 248/454, 455, 456, 457, 460; 361/679.04, 361/679.05, 679.06, 679.02, 679.07, 679.09, 361/679.21, 679.26, 679.3, 379.55, 679.56

(57) **CLAIM**

The ornamental design for a supporter for portable computing device, as shown and described.

DESCRIPTION

FIG. 1 is a perspective view of a supporter for portable computing device showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.
